UNITED STATES PATENT OFFICE.

ALEC JOHN GERRARD AND PARVIN WRIGHT, OF CHICAGO, ILLINOIS.

WIRE BALE TIE.

Application filed January 16, 1923. Serial No. 613,058.

To all whom it may concern:

Be it known that we, ALEC JOHN GERRARD and PARVIN WRIGHT, respectively, a subject of the King of Great Britain, and a citizen 5 of the United States, both residing at Chicago, in the county of Cook and State of Illinois, have invented certain new and useful Improvements in Wire Bale Ties; and we do hereby declare the following to be a full, 10 clear, and exact description of the invention, such as will enable others skilled in the art to which it appertains to make and use the same.

This invention relates to wire bale ties, 15 and has for its object to provide an article of this nature which will be capable of use in a variety of different machines.

With these objects in view, the invention consists in the novel details of construction 20 and combinations of parts more fully hereinafter disclosed and particularly pointed out in the claims.

Referring to the accompanying drawings forming a part of this specification, in 25 which like numerals designate like parts in all the views:

Figure 1 is a diagrammatic view illustrating one type of machine capable of employing only tie wires having deformed ends; 30 Figure 2 indicates one of the holding posts employed in a machine such as that shown in Figure 1;

Figure 3 is an end view of the post shown in Figure 2 with the deformed end of the 35 wire applied thereto;

Figure 4 is a knot tied by the machine shown in Figure 1;

Figure 5 is a plan view of a portion of a 40 wire bale tie made in accordance with this invention;

Figure 6 is a diagrammatic view showing how the wire of Figure 5 may be applied to a type of machine different from that shown in Figure 1; and

Figure 7 is a diagrammatic perspective view illustrating how the wire shown in Figure 5 when used on other machines, may be tied with the well known knots in common use.

In order that the invention may be the more clearly understood, it is said:

In the copending application of A. J. Gerrard and Parvin Wright, No. 541,777, filed March 7, 1922, entitled Wire tensioning and twisting machines, there is disclosed in detail a machine of the character

shown in Figure 1, and also there is disclosed the advantages of a knot made from a tie wire with the deformed end on such a machine. Briefly, these advantages reside 60 in the fact that the extreme ends of the finished knot are bent down alongside of the adjacent bights of the wire so that they do not project up to tear the hands of the operator or to tear boxes or packages which 65 may be slid over said knots during shipment. Such objections are very common in knots of this character made from wires not having deformed ends, as is well known.

Briefly stated, the disclosure of said co-pending application makes it quite clear 70 that a tie wire such as 1 having a deformed end such as 2 when placed in the post 3 of a machine such as 40 may be held by said post while the bight 4 of said wire is passed 75 down one side of a box or package 50 and the bight 6 is passed up on the other side of said box. Said bight 6 is also passed into the slot 7 of the post 3, through a portion 8 of the machine 40 containing the wire twisting mechanism (not shown), then through a slotted post 9 and around a tensioning mechanism 10, whereupon the operation of the lever 11 will put any desired tension upon said wire and a turning of the handle 80 12 will operate the twisting mechanism to twist the parts together to form the knot shown in Figure 4. Said disclosure also 85 makes it clear that the post 3 as indicated in Figure 3 is provided with a projection or 90 lip 13 which when strain is brought upon the bight 4 causes the extreme end 14 of the wire to be turned down slightly as plainly shown in Figures 3 and 4, so that said end 14 lies down alongside of the bight 6 of the 95 knot and thus does not tear the hands or packages when rapidly passed over said knot.

Said disclosure further makes it clear 100 that after the bights 4 and 6 have been thus twisted together, as illustrated, a cutter 17 surrounding the post 9 cuts off the bight 6 and in so doing turns down the extreme end 18 of the finished knot alongside of the bight 4 and thus prevents said end from 105 projecting up above said bight and tearing the hands or packages when passed over said knot.

Machines operating as above disclosed for 110 making knots like those just described are well known on the market and have gone into extensive use. But there are a num-

ber of other types of machines which require loops such as 20 in the ends of the tie wires they use, for these loops must be adapted to fit around lugs, projections or pins such as 21 shown in Figure 6, in order to hold these wires in the machines when tension is being applied. Still other types of machines do not employ pins such as 21, but they require the loops 20 nevertheless, 10 for said loops are manipulated in other ways well known to those skilled in the art. These loops 20 are not adapted for use in the type of machines shown in Figure 1, and therefore, when a gang of workmen are provided 15 with different types of machines, some requiring tie wires having deformed ends 2, such as those above illustrated, and some requiring loops such as 20, there is generally experienced vexatious delays and confusions, 20 owing to the fact that the tie wires are not interchangeable from one machine to another. In fact, there is a greater variety of machines requiring loops than of those requiring deformed ends, although the knots 25 of the latter are far superior to the knots of the former. It is therefore very desirable indeed to supply a tie wire which will be capable of a so called universal use in all of the various types of machines now on 30 the market. This has been accomplished by the provision of the loop 20 on one end of the tie wire 1, and the deformed portion 2 on the other end of the said tie wire, so that when a machine of the type shown in 35 Figure 1 requires a bale tie, the deformed portion 2 may be fitted into its post 3 and the looped end cut off, while if another type of machine requires the loop form of tie wire, the loop 20 may be fitted into the 40 machine, or used by it, and the deformed end cut off after the knot is made. When the deformed end 2 is fitted into a machine such as that in Figure 1 and the loop end is cut off by the revolving cutter 17, the knot appears 45 as in Figure 4, which is a very superior knot as above stated. On the other hand, when the looped end of the wire is required to be fitted into the machine or is otherwise manipulated by the machine, a 50 type of knot illustrated at 22 in Figure 7 results. That is to say, the deformed end 2 is passed through the loop 20 and the wire is twisted around the bight 4 as indicated. In such cases, the end portion 2 is cut off 55 by suitable mechanism, not shown. But again, in some machines of the general type of Figure 1, the looped end 20 of the wire may pass around a post such as 21 located on the left hand side of the machine, as seen 60 in Figure 1, and the deformed end 2 of the

wire is subjected to the tensioning mechanism when the parts are twisted together, and both ends are cut off by cutters not shown. In such cases, the ends such as 4 and 18 may be also tucked down or bent 65 down beside the bights of the wire as will be understood from Figure 4.

It will now be clear that by providing a bale tie wire, with a loop at one end and a deformed portion 2 at its other end, an operator working a gang of men or using a number of different kinds of machines, need only buy and keep track of one kind of tie wire, for he can be assured at all times that each type of machine can be kept 75 in operation so long as there are any tie wires of the type of this invention left in stock. Further, when baling hay or other material under compression, one may pass this wire around the bale in the ordinary 80 way by hand, pass the deformed portion 2 by hand through the loop 20 in the ordinary way and secure it by hand to bight 4 in the ordinary way, so that this tie wire is not only capable of use on the various types 85 of machines, but it is capable of hand manipulation in baling presses. A further decided advantage in this type of bale tie wire accrues to the manufacturer, in that he may readily not only standardize the wires to a single type but he can also standardize the 90 shipping packages containing the same to a single type, thus saving not only in the cost of the various machines necessary to make different types of wire, but also saving 95 in the cost of packaging different types of wire.

What is claimed is:

1. A bale tie comprising a wire having a flattened deformed portion on one of its ends, and a loop portion on the other of its ends.
2. A bale tie wire provided on one of its ends with a deformed portion of a diameter less than the thickness of the wire and on 105 its other end with a loop.
3. A wire bale tie provided with a flattened deformed portion on one end and with a twisted portion forming a loop on its other end.
4. A wire bale tie capable of use in different types of machines and provided on one of its ends with a flattened deformed portion terminating in a holding shoulder, and on its other end with a holding loop.

In testimony whereof we affix our signatures.

ALEC JOHN GERRARD.
PARVIN WRIGHT.
